UNITED STATES PATENT OFFICE

142,024

DESIGN FOR A PRESS WITH INDEXING TABLE

William C. Denison, Jr., Powell, Ohio, assignor to
The Denison Engineering Company, Columbus,
Ohio, a corporation of Ohio

Application November 30, 1944, Serial No. 116,622

Term of patent 14 years

(Cl. D63—1)

To all whom it may concern:

Be it known that I, William C. Denison, Jr., a citizen of the United States, residing at Powell, in the county of Delaware and State of Ohio, have invented a new, original, and ornamental Design for a Press with Indexing Table, of which the following is a specification, reference being had to the accompanying drawing, forming a part thereof, in which

Figs. 1 and 2 are side and front elevational views

respectively of a press with indexing table, showing my new design.

The general appearance of that side of the machine which is not illustrated is approximately the same as that which is illustrated.

I claim:

The ornamental design for a press with indexing table, substantially as shown and described.

WILLIAM C. DENISON, JR.
